UNITED STATES PATENT OFFICE.

CESARE BARBIERI, OF NEW YORK, N. Y., ASSIGNOR TO THE VORTEX MFG. CO., OF CHICAGO, ILLINOIS, A CORPORATION OF ILLINOIS.

CUP DISPENSER.

Application filed September 26, 1924. Serial No. 739,982.

This invention relates to an improved nested flat cup dispenser of the bottom outlet type wherein chain mechanisms are adapted to carry a stack of nested flat cups downwardly between suitable guides with the tips of the cups adapted to be projected between rollers supported on pivoted arms which are adapted to swing outwardly when a cup is removed by drawing the same downwardly 10 between the said rollers whereby mechanisms are operated to cause the chain mechanisms to automatically advance a predetermined distance for the purpose of lowering the stack of cups to position the lowermost cup 15 in the stack in a position to be readily withdrawn from the dispenser casing.

It is an object of this invention to provide a nested flat cup dispenser wherein nested cups are carried downwardly through the 20 dispenser casing by chain mechanisms which are automatically operated each time a cup is withdrawn from the bottom of the dispenser.

It is also an object of this invention to 25 provide a nested flat cup dispenser wherein the cups are adapted to be removed by pulling the same outwardly between guide rollers which are supported on pivoted mechanisms adapted when moved outwardly to 30 cause operation of conveyor mechanisms which act to automatically advance a stack of flat nested cups downwardly in the dispenser casing each time a cup is removed.

Another object of the invention is the construction of a nested flat cup dispenser 35 wherein a container is pivotally supported on a mounting plate and has removably mounted on the inner face of the front wall thereof a nested flat cup feeding unit adapted to automatically advance a stack of flat nested 40 cups downwardly through the casing toward discharge position each time a cup is withdrawn through an outlet opening provided at the bottom of the casing.

45 It is a further object of this invention to provide a nested flat cup dispenser wherein one of a pair of cup guide channels is adapted to be moved away from the other guide channel to permit the insertion of a stack of 50 flat nested cups between said guide channels.

It is furthermore an object of the invention to provide a flat nested cup dispenser wherein a container is provided with a re-

movable cup feeding mechanism unit for advancing a stack of cups through the casing 55 a predetermined distance each time a cup is removed from said casing through a discharge opening which is so shaped that the cup as it is withdrawn is prevented from collapsing to permit the creased portions of the 60 cup to pass between the grooved rollers to automatically actuate cup advancing mechanisms within the container.

Still another object of the invention is the 65 construction of a nested flat cup dispenser wherein a mounting plate has a stop plate or tongue mounted thereon projecting through an opening in the lower base portion of a container which is pivoted on the mounting plate and is adapted to be swung into a lowered 70 projecting position to be filled with a stack of flat nested cups with said tongue projecting across the lower end of the path of the cups to act as a stop for said cups when the container is in open position. 75

It is a further object of this invention to provide a flat nested cup dispenser wherein a pivotally mounted container is adapted to be held in closed position by a latch mechanism mounted within a container cover which may be unlocked to permit the container to be swung into a position to permit removal of a cup feed unit which is removably mounted on one of the walls of said container in a position to feed a stack of 80 cups downwardly into a position to permit withdrawal of said cups one at a time 85 through a discharge opening in the bottom of said container.

Still another object of the invention is to 90 provide a nested flat cup dispenser having a container equipped with a cup feed unit which is mounted on a removable plate within the container and having guide rails between which the cups are advanced, one of 95 said rails being adjustable with respect to the other to permit a stack of flat nested cups to be readily inserted between the guide rails or removed therefrom.

Another object of the invention is to provide 100 a nested flat cup dispenser having a removable cup feed unit equipped with a pair of endless chains which are adapted to carry a stack of cups downwardly between guides a predetermined distance each time a cup is 105 removed from the lower end of the dispenser.

causing operation of mechanisms governing the movement of said chains.

It is an important object of this invention to provide a nested flat cup dispenser 5 having a bottom outlet for cups to permit a cup to be withdrawn outwardly through said opening with the cup acting as a medium for causing operation of a plurality of mechanisms adapted to actuate endless conveyors which act to conduct a stack of flat nested cups downwardly a predetermined distance between inclined guides each time a cup is withdrawn from the dispenser.

Other and further important objects of 15 this invention will be apparent from the disclosures in the specification and the accompanying drawings.

The invention (in a preferred form) is illustrated on the drawings and hereinafter 20 more fully described.

On the drawings:

Figure 1 is a front elevation of a flat nested cup dispenser embodying the principles of this invention.

25 Figure 2 is a fragmentary rear elevation of the dispenser.

Figure 3 is an enlarged bottom plan view of the dispenser.

Figure 4 is a longitudinal sectional view 30 taken on line 4-4 of Figure 1.

Figure 5 is an enlarged fragmentary detailed section taken on line 5-5 of Figure 1.

Figure 6 is a fragmentary detailed section 35 taken on line 6-6 of Figure 2 with parts omitted.

Figure 7 is an enlarged fragmentary view taken on line 7-7 of Figure 5 showing the cover locking mechanism.

40 Figure 8 is a detailed section taken on line 8-8 of Figure 7.

Figure 9 is an interior view of the casing taken on line 9-9 of Figure 4.

45 Figure 10 is an enlarged sectional view taken through the lower end of the casing on line 10-10 of Figure 4 with parts shown in elevation.

Figure 11 is a side view of the portion of 50 the device illustrated in Figure 10.

55 Figure 12 is a bottom plan view of the cup feeding unit removed from the container.

Figure 13 is a fragmentary detailed view 55 taken on line 13-13 of Figure 12 showing a cup in position.

Figure 14 is a detailed section taken on line 14-14 of Figure 9 with the casing omitted.

60 Figure 15 is a fragmentary detailed view taken on line 15-15 of Figure 12.

Figure 16 is a detailed view similar to Figure 10 taken through the lower portion of a modified form of flat cup dispenser.

65 Figure 17 is a side view of the mechanism 65 illustrated in Figure 16.

Figure 18 is a bottom plan view of the modified form of the cup feed unit removed from the casing.

Figure 19 is an enlarged detailed section taken on line 19-19 of Figure 17. 70

As shown on the drawings:

Referring to Figures 1-15 inclusive the reference numeral 1 indicates a back plate or mounting plate having a plurality of apertures 2 therein for the purpose of receiving mounting screws to hold the mounting plate in position upon a wall or other support. The mounting plate 1 is provided with an integral rearwardly directed flange 3 on the side and bottom edges thereof to 80 hold the mounting plate spaced from the wall. Rigidly secured longitudinally on the back face of the mounting plate 1 are the upper and lower ends of a channel guide strap 4 through which the bight or connecting link of a U-shaped bail or suspension member 5 projects. The bight of the bail 5 is adapted to slide upwardly and downwardly between the mounting plate 1 and the strap 4 with the arms of said bail 90 projecting through longitudinal slots 6 provided in the mounting plate 1 (Figure 2). Projecting through an opening 7 in the lower portion of the mounting plate 1 is the split end of a stop strap or tongue 8 which 95 normally hangs downwardly with the lower end thereof contacting the front face of the mounting plate 1 as illustrated in Figure 4. The upper end of the tongue 8 has the split portions or lugs 9 bent in opposite directions 100 against the rear surface of the mounting plate 1 to prevent the tongue from sliding through the opening 7. Mounted on the rear face of the lower portion of the mounting plate 1 below the aperture 7 is a hinge 105 10 to which the lower margin of a casing or container back plate 11 is pivotally connected. The container back plate 11 is provided with an opening 12 through which the stop tongue 8 projects. The container comprises a front wall 13 and integral side walls 14. The lower portion of the front wall 13 is bent inwardly or inclined at 15 to integrally connect up with an arched bottom plate 16 having a cup outletting slot 17 115 therein with the middle portion of said slot enlarged as indicated by the reference numeral 18. The lower middle portion of the inclined wall 15 of the container front wall is formed to provide a rounded thumb recess 19. Rigidly secured to the inner face of the container side walls 14 are brackets 20 (Figure 9) to which the ends of the arms of the bail 5 are pivotally connected. The bail 5 acts as a suspension support for holding the container supported in a lowered open position as illustrated in Figure 6.

Mounted on the upper edge of the mounting plate 1 is a hinge 21 for pivotally supporting the rear portion of a top plate or 130

cover 22 in position. The cover 22 is provided with front and side flanges 24 adapted to fit over the upper end of the container when the container is in closed position. A boss 25 is integrally formed in the top of the cover 22 and has an opening 26 (Figure 5) therein to permit a key to be inserted through the cover for the purpose of unlocking the latching mechanism to permit the cover to be raised and the container to be lowered.

The cover latching mechanism is mounted on the inner face of the cover 22 and comprises a channel strap 27 the ends of which are secured to the inner surface of the cover. Pivotally supported by the strap 27 by means of a pin 28 is a latch bar 29 having a pair of key receiving openings 30 therein below the opening 26 in the cover boss 25. One end of the latch bar 29 is depressed to form a head or tip 31 which, when the latch bar 29 is in locking position, is adapted to latch or engage beneath a flange 32 which is integrally formed at an angle on the upper edge of a removable plate 33 which is adapted to be secured in place adjacent the inner surface of the front wall 13 of the container. Struck inwardly from the cover 22 are nubs or projections 34 and 35 which are positioned on opposite sides of the latch bar 29 as illustrated in Figures 7 and 8. The nub 34 is slightly higher than the nub 35 and acts as a stop for limiting the swing of the latch bar 29 in one position. The nub 35 is shorter than the nub 34 and is low enough to permit the rear end of the latch bar 29 to be forced over the same when a key is inserted into the latch bar apertures 30 to swing the latch bar into a release or open position out of latching engagement with the flange 32 of the plate 33.

The mounting plate 33 is provided with an opening 36 into which a tongue 37 projects. The tongue 37 forms an integral part of the plate 33 as illustrated in Figure 9. The plate 33 is adapted to be removably placed within the container against the inner surface of the container front wall 13 with the lower edge of the plate 33 seating in brackets 38 which are rigidly secured on the inner surface of the container front plate 13 as illustrated in Figures 6 and 9. Rigidly secured to the inner face of the container front wall 13 near the front end thereof are the ends of a strap 39 through which the tongue 37 on the plate 33 is adapted to engage as illustrated in Figure 9 to hold the plate 33 removably secured in a position within the container.

The plate 33 is adapted to serve as a mounting for the cup feed mechanisms and affords a removable unit. Rigidly secured to one face of the plate 33 is the flange 40 of a cup guide channel 41. The guide channel 41 is inclined as illustrated in Figure 9 with

the upper end of the guide channel nearer the side wall 14 of the container than the lower end of said guide channel. Struck from the upper end of one of the walls of the guide channel 41 is an outwardly curved finger 42 over which an endless conveyor chain 43 is trained. The chain 43 passes downwardly through the guide channel 41 and near the bottom of said guide channel, passes out of an opening 44 and through an opening 45 and engages around a sprocket 46 and then passes upwardly between the guide channel 41 and one of the side walls 14 of the container. The sprocket 46 is rigidly secured to or formed on one end of a sleeve 47 which is rotatably mounted on a shaft 48 the ends of which are journalled in a U-shaped mounting plate or bracket 49 which is rigidly secured to the lower portion of the guide channel 41. Integrally formed on the opposite end of the sleeve 47 is a ratchet 40 with which a stop pawl 51 coacts to prevent a reverse rotation of said ratchet. A spring 52 is connected to hold the pawl 51 in resilient contact with the peripheral edge of said ratchet. Pivotally mounted on the ends of the shaft 48 are the arms 53 of a channel lever 54 the lower end of which is yoked at 55 to rotatably support a pulley wheel or grooved roller 56. Pivotally mounted on one of the arms 53 of the pivoted lever 54 is an actuating pawl 57 having a spring 58 for resiliently holding the pawl 57 in contact with the teeth of the ratchet 50. Rigidly secured to the lower margin of the mounting plate 33 is a plate 59 the ends of which are bent at an angle to afford a stop 60 and a stop arm 61. The stop arm 61 has a leather or rubber collar or pad 62 secured on the end thereof to afford a resilient stop to limit the inward swing of the lever 54 caused by the action of one arm of the spring 58.

A second guide channel 63 is provided for the cups with said guide channel having integrally formed thereon a flange 62 having one margin thereof turned upwardly at an angle to form a side flange 65. The flange 64 of the guide member 63 is provided with transverse slots 66 (Figure 15) through which pins 67 project with the pins secured to the plate 33. The guide 63 is also inclined with respect to the side 14 of the container so that the two guides 41 and 63 are further apart at their upper ends than at their lower ends so that when a stack of flat nested cups 68 is positioned between said guides their downward movement is retarded and the cups are slightly expanded to permit the same to move toward their discharge position. Slidably mounted upon the flange 64 between one portion of the guide 63 and the side flange 65 is a slideable latch plate 69 having a pair of curved cam slots 70 therein through which the pins 67 also

project. The upper end of the slideable latch plate 69 is bent over at an angle to form a finger piece 71 to permit the latch plate to be actuated to cause the guide 63 to 5 be moved inwardly toward or outwardly away from the stationary guide 41. Also rigidly secured to a portion of the guide 63 is another channel or U-shaped mounting bracket 49. The lever, pawl and ratchet 10 mechanisms at the lower end of the guide channel 63 are the same as those at the lower end of the guide channel 41 and are numbered correspondingly.

As illustrated in Figures 9 and 15, a 15 coiled spring 72 connects the two levers 54 to normally hold the same against the respective stop pads 62 with the rollers 56 in their innermost position to permit the lowermost cup 68 in the stack of cups to project downwardly between said rollers with the tip of the cup projecting through the cup outlet opening 17-18 into an exposed position as illustrated in Figure 1 and behind the thumb opening or recess 19 so that 20 the tip of the cup may be easily grasped by the thumb and forefinger of a person desiring to draw a cup downwardly out of the dispenser. Mounted on the lower central portion of the removable plate 33 is an inclined cup guide 73 which is so positioned that the tip ends of the cups when lowered are adapted to slide over said guide 73 which acts to direct the tips of the cups between the rollers 56 so that the cups when withdrawn from the container will pass through the grooves of the rollers and cause actuation of the levers 54 as hereinafter described.

Figures 16 to 19 inclusive illustrate a modified form of flat nested cup dispenser 40 similar in construction to that illustrated in Figures 1 to 15 inclusive of the drawings, with the exception that the mechanism for operating the ratchets is modified. The various parts of the modified form of invention which are similar in construction to the parts illustrated in Figures 1 to 15 inclusive are numbered correspondingly and no further description of the same is therefore deemed necessary. In the modified form of the invention the pawl mechanisms coacting with the ratchets 50 are omitted and are replaced by spring arms or fingers 74 which are secured to the levers 54 and are so positioned so that each time the levers 45 are moved outwardly away from one another to permit discharge of a cup the tips of the resilient fingers 74 are forced to contact with the teeth of the ratchets 50 to cause the ratchets to be rotated a predetermined 50 distance to feed the stack of cups downwardly through the container each time a cup is withdrawn through the outlet slot in the bottom of the container.

The operation is as follows:

65 The dispenser is adapted to be mounted

upon a wall or support by securing mounting screws through the apertures 2 of the mounting plate 1 so that the flanges 3 of said mounting plate are held in contact with the wall. With the dispenser mounted in 71 the position as illustrated in Figure 1, a key is inserted through the opening 26 in the cover 22 to engage in the apertures 30 of the latch bar 29. By turning the key, the latch bar 29 is rotated on the pivot pin 28 thereby forcing the inner end of said latch bar away from the stop 34 and over the projection 35 while the latching end 31 of the latch bar is moved out of latching engagement with the locking flange 32 thereby unlocking 81 the cover 22. The cover 22 may now be swung upwardly into open position thereby releasing the container 13-14 which may be swung downwardly about the hinge 10 into the position illustrated in Figure 6. 81 With the downward movement of the container, the bight of the supporting member 5 slides downwardly in the guide strap 4 so that the arms of said supporting member 5 act to hold the container supported in open 91 position. As hereinbefore mentioned, the cup feed mechanisms are all mounted upon the removable mounting plate 33 which is supported adjacent the inner surface of the container front wall 13 by the supporting 91 brackets 38 and by the tongue 37 which projects through the strap 39 as illustrated in Figure 9. The cup feed mechanisms thus consist of a removable unit which may be easily removed from the container or placed 101 therein.

With the container in its lowered open position, an operator may engage the finger piece 71 (Figure 15) and pull upwardly on the same thereby causing the latch plate 69 10 to slide outwardly over the flange 64 of the guide member 63. Outward movement of the latch plate 69 causes the slots 70 to pass over the pins 67 thereby causing both the latch plate 69 and the guide 63 to slide 11 transversely or move outwardly away from the guide 41 with the slots 66 passing over the pins 67. It will thus be noted that the guides 41 and 63 are adapted to be readily moved apart or separated to increase the distance therebetween so that a stack of flat nested cups 68 may be readily inserted through the top of the container between the separated guides 41 and 63 with the creased ends or corners of the open ends of the cups 12 in contact with the conveyor chains 43 as illustrated in Figure 10. The stack of cups are pushed downwardly until the lowermost cup slides over the guide 73 and is directed or guided into the enlarged portion of the cup outlet slot 17. The stack of cups is not moved into its lowermost position when the container 13-14 is lowered due to the fact that when the container is lowered the tongue 8 projecting through the 13

opening 12 and assumes the position illustrated in Figure 6 across the enlarged portion 18 of the outlet slot and acts as a stop against which the tip of the lowermost cup is adapted to engage.

With a stack of cups positioned between the guides 41 and 63 in contact with the conveyor chains 43, the latch plate 69 is pushed downwardly into normal position thereby causing the movable guide 63 to move inwardly toward the stationary guide 41. The corners of the cups 68 are thus compressed by the chains thereby causing the open ends of the cups to partially open 15 due to the pressure caused by the movable guide moving back into its normal position.

The container is now swung upwardly against the mounting plate 9 with the stop tongue 8 swinging rearwardly toward the mounting plate 1 thereby permitting the stack of cups to be gradually lowered so that the tip of the lowermost cup will project between the grooves of the guide rollers 56 into an exposed position as illustrated in Figure 1. The cover 22 is now closed and the head 31 of the cover latch 29 is moved back into latching position beneath the retaining flange 32 on the upper end 25 of the plate 33. To remove a cup from the container, the thumb of an operator is inserted through the thumb recess 19 against the exposed tip of the lowermost cup 68 while the fore-finger of the person's hand is engaged against the back of the tip. The lowermost cup may now be pulled downwardly through the outlet opening 17 in the base of the container.

As the lowermost cup is being drawn 40 downwardly, the creased edges of the cup ride between the rollers 56 thereby gradually rotating said rollers and gradually forcing the two pivoted levers 54 outwardly 45 away from one another against the resistance of the connecting spring 72. As the levers 54 are swung outwardly from the position illustrated in Figure 15, the actuating pawl 57 on said levers act to rotate the ratchets 50 a predetermined distance to cause a partial 50 rotation of the sleeves 47 and the sprockets 46 mounted thereon. Rotation of the sprockets 46 causes movement of the continuous chains 43 which in turn act to carry the stack of cups 68 downwardly in the container a predetermined distance each time a cup is withdrawn from the dispenser. After a cup has been withdrawn from the dispenser, the spring 72 acts to pull the levers 54 inwardly against the stop pads 62. 60 The pawls 51 which are in engagement with the ratchets 50 act to prevent a reverse rotation of the ratchets and the conveyor chains.

The guide 73 in the lower end of the conveyor is provided to conduct the tips of the

lowermost cups between the rollers 56. It will be noted that the cups within the container may be removed one at a time as already described with the remaining stack of cups being moved downwardly through the container by the conveyor chains 43 a predetermined distance each time a cup is removed. When all the cups have been removed from the container, the same may again be easily filled as already described. 75

When a cup is withdrawn from the lower end of the container the creased portions of the cup ride in the grooves of the rollers 56 with the tip of the cup projecting through the enlarged portion 18 of the outlet slot 80 17. The slot 17 is restricted in width at its ends as illustrated in Figure 3 in order that the creased margins of the cups will be prevented from collapsing in order that a cup as it is withdrawn will be of sufficient 85 strength to cause the levers 54 to move outwardly away from one another to cause operation of the cup feed mechanisms.

In the modified form of dispenser illustrated in Figures 16 to 19 inclusive, the operation is substantially the same as that already described with the exception that when a cup is being withdrawn through the bottom of the container the cup acts to swing the pivoted levers 54 outwardly away 90 from one another so that the pawl fingers 74 on said levers will actuate the ratchets 50 and thereby cause operation of the cup feed chains 43 whereby the stack of cups within the container is advanced downwardly toward discharge position a predetermined distance each time a cup is withdrawn through the outlet opening in the bottom of the container. 100

I am aware that many changes may be made, and numerous details of construction may be varied through a wide range without departing from the principles of this invention, and I therefore do not purpose limiting the patent granted hereon, otherwise than necessitated by the prior art. 105

I claim as my invention:

1. A nested flat cup dispenser comprising a mounting plate, a container pivotally mounted thereon, a cover for the container pivotally mounted on the mounting plate, means connecting the mounting plate and the container for holding the container supported in place in open position, and a stop supported on the mounting plate and projection through a portion of the container to act as a stop for cups when the container is in open position. 115

2. A nested flat cup dispenser comprising a mounting plate, a container removably supported thereon and having an opening therein, and a cup stop member engaged on the mounting plate and projecting through the opening in said container. 125

3. A nested flat cup dispenser comprising 130

- a mounting plate, a container and cover pivotally mounted thereon, a plate removably supported in said container, cup feed mechanisms on said plate, and latching mechanisms mounted within said cover adapted to engage said plate to hold the container locked in closed position.
4. A nested flat cup dispenser comprising a container, a cover therefor, a cup feed mechanism within said container adapted to be removed therefrom as a unit, and latching means within the cover adapted to removably engage a portion of said cup feed mechanisms to hold the cover locked on the container.
5. A nested cup dispenser comprising a casing, a cup feed unit removably mounted in said casing, a mounting for said casing, means slidably mounted on said mounting and projecting into the casing for the purpose of supporting the casing in its open position, and a tongue supported on said mounting adapted to project through a portion of the casing when the same is moved into open position to act as a resilient stop for a stack of cups to hold said cups away from a discharge position.
6. A nested cup dispenser comprising a casing, a plate removably mounted within said casing, cup guides mounted on said plate, endless chains moving through said cup guides to carry a stack of cups between said guides, and mechanisms supported by the guides for actuating said chains each time a cup is withdrawn from the casing to actuate said mechanisms.
7. A nested cup dispenser comprising a casing, a plate removably supported therein, guides mounted on said plate, chains in said guides, levers pivoted on said guides, rollers on said levers and mechanisms mounted on said levers co-acting with said chains and adapted to be actuated by said levers each time a cup is withdrawn from the casing to cause the levers to operate said mechanisms and cause the chains to feed a stack of cups between said guides and rollers.
8. A nested cup dispenser comprising a casing, a plate removably mounted therein, a stationary guide and a movable guide on said plate, means for adjusting said movable guide with respect to said stationary guide, endless means passing through said guides for carrying a stack of nested cups, and mechanisms supported on said guides adapted to be operated by the withdrawal of cups from the casing to cause advance of said endless means to feed the stack of cups through the container between said guides each time a cup is removed from the casing.
9. A nested cup dispenser comprising a casing, a stationary guide and a movable guide mounted therein, endless means passing through the guides for conducting a stack of nested cups through the container, mechanisms for actuating said endless means, and spring controlled pivoted members connected with said mechanisms adapted to be actuated each time a cup is withdrawn from the casing to cause said mechanisms to operate the endless means and advance the stack of cups a predetermined distance in the casing.
10. A nested cup dispenser comprising a casing, a plate removably mounted therein, a stationary guide on said plate, a movable guide on said plate, means for adjusting said movable guide with respect to the stationary guide, endless chains passing through said stationary and movable guides, mechanisms for operating said chains, pivoted levers connected to operate said mechanisms, and rollers on said pivoted levers adapted to be engaged by a cup as it is withdrawn from the casing to permit the cup to actuate said pivoted levers and operate said mechanisms to cause the endless chains to advance the stack of cups a predetermined distance through the casing each time a cup is removed therefrom.
11. A nested flat cup dispenser comprising a casing, a plate removably mounted therein, guides on said plate, means for adjusting one of said guides with respect to the other to permit a stack of nested cups to be engaged between said guides, conveyors passing through said guides for carrying the stack of cups through the casing, levers pivotally supported on said guides, rollers on said levers adapted to be engaged by a cup as it is withdrawn from the casing to cause said levers to be moved outwardly away from one another, stops on said plate limiting the movement of said levers, and mechanisms operable by the movement of said levers to cause the endless conveyors to advance the stack of cups a predetermined distance in said casing between said guides.
12. A flat nested cup dispenser comprising a casing, a plate removably supported therein, a stationary guide on said plate, a movable guide on said plate, means for adjusting said movable guide with respect to said stationary guide to permit a stack of flat nested cups to be inserted between said guides, endless conveyors mounted to move through said guides, levers pivotally supported on said guides, rollers on said levers, a spring connecting said levers, stops on said plate for limiting the movement of said levers, and pawl and ratchet mechanisms on said levers adapted to be actuated thereby to cause movement of said endless conveyors to feed the stack of cups through the casing between said guides.
13. A flat nested cup dispenser comprising a casing, a plate removably mounted therein, a stationary guide mounted on said plate, a movable guide mounted on said

- plate, means for adjusting the movable guide with respect to the stationary guide to permit a stack of flat nested cups to be positioned between said guides, endless chains supported on and passing through said guides, mechanisms for rotating said chains, pivoted members for actuating said mechanisms to cause movement of said chains and advance of the stack of the cups through 10 said casing between said guides, stops mounted on said plate, resilient means connected with said pivoted members for holding the same against said stops, rollers on said pivoted members, and a guide mounted on 15 said plate adapted to direct the cups between said rollers, said cups adapted to be removed from the casing one at a time between the rollers to cause actuation of the pivoted members and operation of said 20 mechanisms and endless chains.
14. A flat cup dispenser comprising a casing, guides mounted therein, means for adjusting the guides with respect to one another, continuous means for carrying a stack 25 of cups between said guides, and pivoted mechanisms adapted to be automatically actuated by the withdrawal of a cup from said casing to cause actuation of said continuous means and feeding of said stack of cups between said guides. 30
15. A nested cup dispenser comprising a plate, guides mounted on said plate, means for adjusting one of said guides with respect to the other to permit a stack of flat nested cups to be inserted between said guides, endless chains supported on said guides and passing through the guides to afford means for carrying the stack of cups, mechanisms on the guides for causing rotation of said chains, spring controlled levers for operating said mechanisms, and rollers on said levers adapted to be engaged by the withdrawal of a cup to cause said levers to actuate said mechanisms and rotate the chains. 35
16. A flat cup dispenser comprising a casing, a mounting plate removably mounted therein, a guide secured to said mounting plate, a second guide movably mounted on said mounting plate, and a latch plate slidably mounted on said movable guide adapted to be actuated to cause the movable guide to be adjusted with respect to said stationary guide. 40
- In testimony whereof I have hereunto subscribed my name.

CESARE BARBIERI.
